SPLITTING MACHINE

Frank Kennison and Harry L. Bell, Beverly,
Mass., assignors to United Shoe Machinery
Corporation, Flemington, N. J., a corporation
of New Jersey

Application August 1, 1940, Serial No. 349,372

10 Claims. (Cl. 12—17)

This illustration relates to splitting machines and is illustrated as embodied in a machine for splitting heel-breast covering flaps from soles of shoes.

It has been proposed to prefinish soles prior to their attachment to shoes, the sole, for example, being conveniently rough-rounded, shank-reduced, and edge-set, and in the case of compo work, roughed up at its flesh side by the use of a machine disclosed in United States Letters Patent No. 2,078,981, granted May 4, 1937, and No. 2,081,961 granted June 1, 1937, on applications filed in the name of Ernest W. Stacey. It has been found that when a prefinished sole is split by an Empire splitting machine of the well-known type, which will hereinafter be referred to as the regular machine, and which comprises a yieldable work support or bed having throughout its extent sharp upstanding prongs upon which the sole is impaled during the splitting operation, the penetration of the sole by the prongs is likely to mar the appearance of its finished marginal portions. Moreover, when the shank portions of the soles, in the case of compo work, are reduced by exceptionally wide beveling cuts, the thin lateral margins of said shank portions are not as effectively supported as desirable throughout their entire areas against the action of a drag bar of the regular machine which acts upon the grain side of the sole in advance of a splitting knife and by its position with relation to the knife determines the thickness of the sole, with the result that the marginal edges of the flap are not split to uniform thickness. In some cases it is the practice to apply cement or other suitable adhesive to the roughed-up margins of the sole, with the result that the margins of the shank portion of the sole are curled slightly toward the flesh side of the sole and must be straightened out effectively by being supported by a continuous surface in order that the lateral edges of the flap split from the sole shall be of uniform thickness.

It is an object of the present invention to provide an improved machine of the above-mentioned type to quickly and effectively split heel-breast covering flaps from prefinished soles of different sizes and shapes without danger of spoiling the prefinished margins of said soles.

With the above object in view and in accordance with a feature of the present invention, there are provided a yieldable bed comprising a block having rigid prongs for supporting the median part of the heel end portion of a sole, a pair of conformable pads for supporting the

remaining heel end portion of the sole, a knife for splitting a heel-breast covering flap from the sole, a presser member constructed and arranged to act upon the sole in advance of the knife and by its position with respect to the knife to determine the thickness of the flap produced by the action of the knife, and means for effecting relative translatory movement between the bed on the one hand and the knife and the presser member on the other hand to produce said flap.

During the flap splitting operation, the median part of the heel end portion of the sole is forced against the prongs of the block, thereby effectively insuring against slippage of the sole on the work bed, the remaining heel end portion of the sole being forced with considerable pressure against and into the conformable pads, which are preferably made of rubber. By providing the bed of the machine with conformable rubber pads, the entire lateral margins of the heel end portions of soles of different sizes and shapes are supported throughout their extent to their extreme marginal edges against the action of the presser member, which has the form of a drag bar, during the flap splitting operation. When the lateral margins of the heel end portion of the sole are supported throughout their entire extents by the rubber pads during the flap splitting operation, there is no danger of piercing them and thus spoiling their appearance.

The various features of the invention will be understood and appreciated from the following detailed description read in connection with the accompanying drawings, in which,

Fig. 1 is a perspective view, partly in section and partly broken away, of an illustrative flap splitting machine;

Fig. 2 is a sectional view, partly broken away, on line II—II of Fig. 1;

Fig. 3 is a sectional view, partly broken away, on line III—III of Fig. 1, during a portion of the flap splitting operation;

Fig. 4 is a plan view of the work bed of the illustrative machine;

Fig. 5 is a section on line III—III of Fig. 1 showing a portion of the work bed of the machine when said machine is idle;

Figs. 6 and 7 are sectional views, partly broken away, corresponding to Fig. 5 but showing modified types of work beds;

Fig. 8 is a perspective view of a sole which has been operated upon by the machine disclosed in said Letters Patent No. 2,081,961;

Fig. 9 is a perspective view of the sole of Fig. 8

after a flap has been split therefrom by the illustrative machine; and

Fig. 10 is a side elevation, partly broken away, of the sole shown in Fig. 9.

The illustrative machine, with the exception of a work bed 20, is substantially identical with the machine disclosed in Letters Patent No. 1,224,918, granted May 8, 1917, on an application filed in the name of Frederick M. Furber, and comprises a reciprocating carrier 22 which is mounted on ways 24 of the frame of the machine and to which a knife 26 is adjustably secured by screw-and-slot connections 28. Fitting in aligned bores 30 (Fig. 3) of the carrier 22 are trunnions 32 of a matrix or drag bar 34, which may be referred to as a presser member and which is constructed and arranged to act upon the grain side of a sole 36 in advance of the knife 26 during the forward reciprocation of the carrier over the work bed 20, and by its position with respect to the bed and the knife to determine the thickness of a flap 38 (Figs. 9 and 10) split from the sole by the knife during its forward movement. The carrier 22 and the mechanism for operating the same are fully described in said Letters Patent No. 1,224,918, which should be referred to for a detailed description of said machine.

Although the invention is described with reference to the machine disclosed in said Letters Patent No. 1,224,918, it will be appreciated that the illustrative work bed 20 may be effectively used in connection with machines such as disclosed in United States Letters Patent No. 1,992,952, granted March 5, 1935, on an application filed in the name of Charles Edward Johnson, and also in connection with machines such as disclosed in United States Letters Patent No. 2,118,825, granted May 31, 1938, on an application filed in the name of Thomas H. Seely, which machines are adapted to split from soles heel-breast covering flaps which are reinforced at their central or central base portions in order to strengthen the flaps at the localities desired.

The illustrative sole 36, shown in Fig. 8, has already been operated upon in the machine disclosed in said Letters Patent No. 2,081,961, the shank portions, as well as the foreparts, of the soles having been rough-rounded and edge-set to their final shapes and the shank portions of the soles having been reduced by exceptionally wide beveling cuts, the margin of the flesh side of the sole, in the case of soles for use in connection with compo work, having been roughed up. As above stated, it is sometimes the practice to apply cement to the roughed up margin of the sole prior to splitting the flap from the same.

As disclosed in United States Letters Patent No. 1,224,918, the work bed 20 comprises a U-shaped frame 40 having in each of its two depending flanges three slots 42 for receiving rollers 44, respectively, pivoted upon the ends of rods 46 secured to a support 48 which rests upon four or more springs 50 (Fig. 3, only two shown) and which, when the machine is idle, is forced by the springs against the heads of two or more stop screws 52 threaded into the base of the machine frame. The slots 42 are parallel to each other, the arrangement being such that when the U-shaped frame 40 is moved forwardly or rearwardly, that is, in the general direction of movement of the carrier 22 over the work bed 20, the frame will be raised or lowered according to the direction of such movement. When the machine is at rest, the U-shaped frame 40, and therefore the work bed 20, is held in its low-

ered position by a coil spring 54 (Fig. 2) encircling a rod 55 the forward end of which is secured to the support 48 and the rear end of which passes through a recess 58 in a block 60 secured to the under side of the U-shaped frame 40, the rod 56 having a stop nut 62 threaded onto its rear end.

The carrier 22 is reciprocated along the ways 24 through a connecting rod 64 (Figs. 1 and 2) the forward end of which is pivoted upon a fulcrum pin 66 mounted upon the carrier and the rear end of which is pivoted upon a bushing 68 (Fig. 1) mounted upon a threaded bolt 70. The bolt 70 may be secured to a rotatable operating plate 72 with its head arranged in different adjusted positions along an arcuate slot 74 formed in said plate, through the provision of a nut 75 threaded onto the upper end of the bolt. The slot 74 is centered about the axis of rotation 76 of the operating plate 72 and, accordingly, the carrier 22 is always moved in a path of fixed extent. It will be noted, however, that the starting position of the carrier may be varied in accordance with the adjustment of the bolt 70 along the slot 74, but that the carrier is always moved forwardly to the same position.

In order that the work bed 20 may be moved to a raised position at a predetermined time during the forward stroke of the carrier 22, preparatory to splitting the sole, said bed carries a pin 78 (Fig. 2) upon which is mounted a roll 80 shaped and arranged to be contacted by an actuating cam 82 during a portion of the cycle of operation of the machine. The actuating cam 82 may be moved about the axis of rotation 76 of the plate 72 into different adjusted positions upon the operating plate 72, as will appear later, through the provision of the above-described connections. When the actuating cam 82 has been properly adjusted upon the plate 72, the nut 75 is tightened to secure the cam to the plate. The forward portion 84 of the outer face 86 of the actuating cam 82 is beveled, the remaining outer face of the cam having the form of a segment of a circle centered about the axis of rotation 76 of the plate 72 and the cam. When the sole is placed upon the work bed 20 and the plate 72 revolves, together with the actuating cam 82, the cam, by contacting the roll 80 (Fig. 2), moves the U-shaped frame 40 forwardly, thereby raising it and holding it in a raised position until the knife 26, which moves forwardly with the carrier 22, has completed the formation of the flap 38. After the flap 38 has been formed and just before the carrier 22 begins its retractive or rearward movement, the roll 80 runs off the trailing end of the face 86 of the actuating cam 82 and the spring 54 moves the U-shaped frame 40 of the work bed 20 to its lowered position, thereby insuring that the drag bar 34 shall not rub heavily on the flap during the retractive movement of the carrier.

In order that the extreme base portion 88 (Fig. 10) of the flap 38 shall be split thicker than the remaining portion of the flap, the drag bar 34 is rotated slightly at the extreme forward end of the stroke of the carrier through mechanism which will now be described. Threaded into the drag bar 34 (Figs. 1 and 2) is a screw 90 upon which is mounted a roll 92 (Fig. 2), which, when the machine is idle, is held in engagement with a stop screw 94 by a spring 96. The connecting rod 64 has a forward extension 98, the opposite sides of which are channeled for the reception of a bracket 100 having an arcuate

cam track 102, the bracket being clamped in a predetermined position to the extension 98 of the connecting rod 64 by screws 104 (only one shown) threaded into the bracket and having their inner ends forced against said extension. Threaded into the forward end of the bracket 100 is another screw 106 which may be turned to facilitate the proper adjustment of the bracket 100 upon the extension 98 of the connecting rod 64. The major portion of the cam track 102 is centered about the axis of the pin 66 so that during the time the roll 92 is in contact with said track, the screw 90, and consequently the drag bar 34, maintains the same angular position. A central portion of the roll engaging face of the track 102 is recessed, the arrangement being such that when the roll 92 encounters said recessed portion near the forward end of the stroke of the carrier 22, the drag bar 34 swings slightly in a clockwise direction, as viewed in Figs. 1 and 2, thereby permitting the springs 50 to raise the work bed, and with it the sole, so as to cause the knife 26 to cut deeper into the sole and thus to form the thickened base portion 88 of the flap. The spring 96 is not strong enough to prevent clockwise movement of the drag bar 34 due to the pull of the drag bar on the sole, the clockwise movement being limited by the engagement of the roll 92 with the track 102.

The work bed 20 also comprises a central block 110 having prongs or teeth 112, sharp edges of which are arranged approximately in a plane, and a pair of rubber pads 114 (Figs. 1, 3, 4 and 5) which are arranged at the opposite sides of the block and, when the machine is idle, have their work engaging faces 113 (Figs. 1 and 5) arranged above or extending beyond the plane of the sharp edges of the prongs 112. The block 110 is rigidly secured by screws 116 (Figs. 3 and 5) to the U-shaped frame 40, and the pads 114 are impaled upon prongs 117 secured to said frame, the end and the outer side margins of the pads 114 being secured to the frame by plates 118 and 120, respectively, screwed to the U-shaped frame 40.

The rubber pads 114 are sufficiently resilient to insure that the soles 36 shall be forced into the pad and be properly supported against action of the drag bar 34 and the knife 26, irrespective of the size or the shape of the sole. It will be appreciated that in order that the conformable pads 114 shall be compressed sufficiently to support the sole firmly, it is desirable that the flat work engaging surfaces 113 of such pads shall extend slightly above the general plane of the sharp edges of the prongs 112, as shown in Fig. 5, when the machine is idle. On the other hand, in order to insure that the sole shall be positively gripped on the work bed 20 during the splitting operation, it is desirable that the median portion of the sole shall be effectively impaled upon the prongs 112 of the block 110. Accordingly, in order to facilitate the flow of the portion of the rubber pad 114 adjacent to the block 110 so that said pad 114 may readily accommodate different sizes of soles, and to insure that the inner margins of the pads shall be properly impaled upon the prongs 112, the upper surface of the U-shaped frame 40 is provided with slight recesses or depressions 122 (Fig. 5), the inner margins of the pads forming with the depressions a pair of small pockets 124. It will be noted that the width of the depressions 122 increases slightly, as illustrated in Fig. 4, as they extend from the

front to the back of the machine, the width of said depressions reaching a maximum at points 126, as shown in Fig. 4. It will be appreciated that, if desirable, the depressions 122 may be of uniform width throughout their length, or may be entirely eliminated, in which case the inner margins of modified pads 128 may be slightly undercut, as shown in Fig. 6, or the inner margins of a modified pad 130 may be honeycombed or otherwise pocketed, as shown in Fig. 7. From the foregoing it will be clear that the inner marginal portions of the pads located adjacent to the block are adapted to flow more readily under pressure of the work piece than the outer marginal portions of the pads.

15 Although the illustrative machine has been described with reference to splitting flaps from soles which have been operated upon by the machine disclosed in United States Letters Patent No. 2,078,981, it will be clear that the illustrative machine may be used for splitting flaps from all types of soles.

20 After the actuating cam 82 has been initially adjusted upon the plate 72, the sole is placed upon the work bed 20 in its desired position and a treadle rod (not shown) is depressed causing the operating plate 72, together with the cam 82, to make a revolution. As the knife 26 and the drag bar 34 move forwardly, the work bed 20 is raised and held raised until the completion 25 of the forward movement of the carrier 22, at which time the spring 54 lowers the work bed and holds it lowered while the carrier moves back to its retracted position. When the carrier 22 is moved forwardly over the work bed 20, as 30 above described, the bar 34 causes the median portion of the sole to be impaled upon the prongs 112 of the block 110 and progressively forces the entire lateral margins of the sole against the pads 114 which effectively support the sole 36 throughout the flap splitting operation without any danger of marring said lateral margins.

35 Having described our invention, what we claim as new and desire to secure by Letters Patent of the United States is:

40 1. A splitting machine having, in combination, a yieldable bed comprising a block having rigid prongs for supporting the median part of the heel end portion of a sole, said bed also comprising a pair of conformable pads for supporting the remaining parts of the heel end portion of the sole, a knife for splitting a heel-breast covering flap from the sole, a presser member constructed and arranged to act upon the surface of the sole in advance of the knife and by its position with respect to the knife to determine the thickness of the flap produced by the action of said knife, and means for effecting relative translatory movement between the bed on the one hand and the knife and the presser member on the other hand to produce said flap.

45 2. A splitting machine having in combination a yieldable bed for supporting a sole, said bed comprising a rigid central portion having a plurality of sharp prongs constructed and arranged to be engaged by the median part of the heel end portion of the sole, said bed also comprising conformable pads which are located at opposite sides respectively of said rigid central portion and are constructed and arranged to be engaged by the lateral margins of the heel end portion of the sole, a carrier, a knife and a presser member mounted upon the carrier, and means for moving the carrier over the bed to cause said knife to split a heel-breast covering flap from the sole as

it is progressively forced against the bed by the presser member.

3. A splitting machine having, in combination, a yieldable bed for supporting a sole, a carrier, a knife and a drag bar mounted upon the carrier, and means for effecting relative translatory movement of the bed and the carrier to cause the sole to be progressively conformed to the drag bar and to be split by the knife, said bed comprising a block having sharp rigid prongs constructed and arranged to be engaged by the median part of the heel end portion of the sole, and a pair of readily conformable pads which are arranged at the opposite sides respectively of the block and which are constructed and arranged to be engaged by the remaining heel end portions of the heel and when the machine is idle extend beyond the prongs.

4. A splitting machine having, in combination, a yieldable bed comprising a block having rigid prongs for supporting the median part of the heel end portion of a sole, and conformable pads normally projecting beyond said rigid prongs and arranged at opposite sides respectively of the prongs for supporting the lateral margins of the heel end portion of the sole, a carrier, a knife and a drag bar mounted upon the carrier, and means for moving the carrier over the sole supported on said bed to cause the bar to force the sole progressively against the work bed and to cause the knife to split a flap from the sole pressed between the bar and the bed.

5. A splitting machine having, in combination, a yieldingly supported frame, a knife, a presser bar, a block secured to the frame and having prongs constructed and arranged to be engaged by the median part of the heel end portion of a sole, and a pair of conformable pads secured to said frame at opposite sides respectively of said block and constructed and arranged to be engaged by the remaining parts of the heel end portion of the sole, said frame having adjacent to the opposite sides of the block shallow depressions the bottoms of which when the machine is idle are spaced from the opposing portions of the conformable pads, and means for moving the knife and the presser member over said bed causing the sole to be progressively forced against the pads and the prongs of said block to conform the sole to a predetermined shape and causing the knife to split a flap from the sole.

6. A splitting machine having, in combination, a sole supporting bed comprising a yieldable frame, a rigid block secured to the frame and having prongs which are constructed and arranged to be engaged by the median part of the heel end portion of a sole and which have sharp ends arranged approximately in a plane, a pair of rubber pads which are secured to said frame and are arranged at opposite sides respectively of the block with their inner marginal portions slightly spaced from the block, said pads having faces which are constructed and arranged to be engaged by the heel end portion of the sole and are normally arranged in a plane disposed above the plane of the sharp ends of said prongs, the outer marginal portions of the pads at all times being firmly supported against the frame and the inner marginal portions of the pads when the machine is idle being spaced slightly from said frame, and means comprising a knife and

a presser member constructed and arranged to cooperate with said bed to split a flap from the sole.

7. A splitting machine having, in combination, a yieldable work support comprising a rigid block having sharp prongs and comprising a pair of conformable pads arranged at opposite sides respectively of said block, a knife, a presser member, and means for effecting relative movement of the work support on the one hand the knife and the presser member on the other hand to cause a work piece upon the support to be progressively conformed to the shape determined by the presser member and to cause a flap to be formed on the conformed work piece by the knife, portions of the pads which are located adjacent to the block being adapted to flow more readily under pressure of the work piece than other portions of the pads which are spaced considerable distances from said block.

8. A splitting machine having, in combination, a yieldable work support comprising a rigid block having sharp prongs and a pair of rubber pads arranged at opposite sides respectively of said block, a knife for splitting a flap from a sole mounted upon said work support, and a presser bar constructed and arranged to act upon the face of the sole in advance of the knife and by its position with relation to the knife to determine the thickness of the flap split from the sole by the knife, portions of the pads which are located adjacent to the block being more readily yieldable under pressure of the sole than are other portions of the pads which are spaced considerable distances from the block.

9. A splitting machine having, in combination, a supporting bed comprising a yieldable frame, a rigid block secured to the frame and having prongs which are constructed and arranged to be engaged by the median part of the heel end portion of a sole, and a pair of rubber pads which are secured to the frame and are arranged at the opposite sides respectively of the block, a presser bar, a knife, means for effecting relative translatory movement of the bed on the one hand and the presser bar and the knife on the other hand to split a heel-breast covering flap from the sole, inner portions of the rubber pads located adjacent to the block being spaced from the block and from the support while outer portions of the pads located considerable distances from the block are secured to the block thereby rendering the inner portions of the pads more readily yieldable than the outer portions of the pads under the action of the sole.

10. A splitting machine having, in combination, a yieldable bed comprising a rigid block having sharp prongs and a pair of rubber pads which are arranged at opposite sides respectively of the block, a knife, a presser member, and means for moving the knife and the presser member over the bed to split a flap from a sole mounted upon said bed, the inner portions of the pads being spaced from the frame and being free to yield toward the block under pressure of the sole so as to insure that the rubber pads may readily flow to accommodate soles of different sizes and shapes during the splitting operation.

FRANK KENNISON.
HARRY L. BELL.
